UNITED STATES PATENT OFFICE.

JOSEPH BANKS, OF DADEVILLE, ALABAMA.

IMPROVEMENT IN PLOWS.

Specification forming part of Letters Patent No. 19,179, dated January 26, 1858.

To all whom it may concern:

Be it known that I, JOSEPH BANKS, of Dadeville, in the county of Tallapoosa and State of Alabama, have invented a new and Improved Subsoil Cultivating-Plow; and I do hereby declare that the following is a full and exact description thereof, reference being had to the accompanying drawings, making part of this specification—

Figure 1 being a side elevation of the plow; Fig. 2, a horizontal section thereof in the plane indicated by the line x x , Fig. 1; Fig. 3, rear view of a portion of the standard C, which supports the handles, showing the method of adjusting the handles.

Like letters designate corresponding parts in all the figures.

To construct the stock of the plow I take three pieces of a bar of iron, each of suitable length, and bend them respectively into the shapes shown in Fig. 1, the hind bar, F, being straight, and the two forward bars, G H, being curved, substantially as shown. The upper ends are secured to the under side of the beam A, respectively by bolts g h i , in the positions shown. The two rear bars, F G, are united by a rivet near their lower ends, which are sharpened in the manner shown. The lower end of the front bar, H, terminates at some distance above the ends of the other two bars, and, being blunt, serves as a shoulder for the rear end of the point L to bear against. A rivet passes through all three of the bars near the lower end of the front bar, H.

The point L, which may be of any desirable form, is laid upon the middle bar, G, its rear end bearing against the end of the bar H, as above specified. A bolt, f, passes through it and the bars F G, whereby it is secured to the stock.

The colter I is constructed and arranged in a peculiar manner. It is made of ordinary size at the upper end, and the lower end divides into three branches, a b c , substantially as represented in Fig. 1. The fore branch, a , curves forward and has a pointed end, which enters a notch in the top of the point L, thereby hold-

ing said point in its proper place and steady-
ing it. The middle branch, b , which is about
in the line of the shank of the colter, enters
notches both in the rear end of the point L and
the lower end of the bar H, and rests therein.
This serves especially to prevent any side
movement of the point, besides giving an ad-
ditional strength as a brace. The hind branch,
 c , extends backward to and bears against the
bar H, which may have a notch for the recep-
tion of the extremity of the branch. Said
branch serves to strengthen the colter at a
point where it is most liable to give way, and
forms a bracing and steadyng connection be-
tween the parts. The shank of the colter ex-
tends through a wide mortise in the beam A,
in which it is secured and adjusted in the right
position by wedges m m , driven down beside
each edge.

I provide an improved mode of adjusting the
handles B B to the desired height in the fol-
lowing manner: The front ends of the handles
are secured against the sides of the beam by a
pivot, e, which allows them to turn thereon. A
supporting -standard, C, extending upward
from the rear end of the beam, is curved a lit-
tle at the top, so as to be concentric with the
pivot e. Said standard is made sufficiently
thick transversely to admit two rows of holes,
 r r , side by side, as shown in Fig. 3. The
stretcher-bar M, which connects the handles,
embraces this standard, and has two holes,
corresponding with two adjacent holes in the
standard, through which bolts t t pass, and
thus hold the handles at the given height.
This mode of securing by double bolts and
holes prevents the side-wresting to which the
handles are otherwise liable.

What I claim as my invention, and desire to
secure by Letters Patent, is—

The combination of the triple-branched colter
I, bars F G H, and point L, constructed and
arranged as herein specified.

JOSEPH BANKS.
